UNITED STATES PATENT OFFICE.

OTTO G. RIESKE, OF DAYTON, OHIO, ASSIGNOR, BY MESNE ASSIGNMENTS,
TO ERNEST B. SCHNEIDER, OF ZANESVILLE, OHIO.

STREET-CAR TURN-TABLE.

SPECIFICATION forming part of Letters Patent No. 661,077, dated November 6, 1900.

Application filed July 22, 1899. Serial No. 724,875. (No model.)

To all whom it may concern:

Be it known that I, OTTO G. RIESKE, a citizen of the United States, residing at Dayton, in the county of Montgomery and State of Ohio, have invented a new Device for Turning Street-Cars, of which the following is a specification.

My invention is a new device for turning street-cars.

10 The objects of my new device of a turn-table are, first, to dispense with loops in order to save land or space and to prevent the breaking of the flanges of the wheels while running on the loop; second, to dispense with Y's, which require the motorman to leave his car to change the trolley; third, each car requires but one controller, thereby saving the expense of a second controller, and, fourth, it enables the motorman to turn the car by its own power without changing the trolley, without any one to help him, and without leaving his place. I attain these objects by the mechanism illustrated in the accompanying drawings, in which—

25 Figure 1 on Sheet 1 is a top view of the table. Fig. 2 shows trucks of the car on the table. Fig. 3 on Sheet 2 shows the mechanism under the table. Fig. 4 shows the base of the table. Fig. 5 on Sheet 3 shows the 30 hub on which the entire table rests. Fig. 6 shows the table complete with car in position.

Similar letters refer to similar parts throughout the several views.

The table A contains two slots B B, through 35 each of which extend two friction-wheels D D, even with the surface of the table A. In the center of the table A is the hub E, through which a steadyng-pin F passes, the same resting on a solid foundation G, the hub E resting on ball-bearing H H. Said friction-wheels D D are connected by shaftings I I in pairs, and the same run through the hubs J J of said friction-wheels D D. The shaftings I I run in journals K K, said journals K K being secured to the bottom of the table A and in this manner holding the friction-wheels D D in position. One of the shaftings I I of said friction-wheels D D is attached to the pinion L by means of the knuckle-coupling M, the 45 pinion L being held in place by a shafting which runs in the journal N, fastened to the

bottom of the table A. Said pinion L runs in the gear O, which is stationary on a solid foundation. The friction-wheels D D in the table A being in even line with the rails of the track P P the car will by running on the table A place itself between said friction-wheels D D. By disconnecting wheels Q of the car and turning on the power of the wheels R of the car, which are seated in friction-wheels D D, the 60 car-wheels will by friction turn said friction-wheels, which will by the knuckle-coupling M bring the pinion L into motion and by revolving in the stationary gear O cause the table A to turn. 65

While the car runs on the table A, the trolley-pole S runs on an incline wire T until the car is seated in the friction-wheels D D, when said trolley-pole S will stand in a vertical position. In turning the car the trolley-pole S is stationary, resting on a pivot U, and the trolley-pole is swiveled, so that the car may turn without turning the pole. After the car has been turned the catch V will hold said table A in proper position, and when 75 power is turned onto the wheels Q the car will be pulled out of said friction-wheels D D, and as the car runs off the table A the trolley-pole S will descend the incline wire T and place itself in proper position. 80

Having described my invention, what I claim, and desire to secure by Letters Patent, is—

1. The combination with a street-car truck of a stationary circular rack, a rotatable 85 plate mounted above said rack and provided with parallel slots, friction-wheels mounted below said plate with their peripheries projected upwardly through said slots and adapted to be engaged by the wheels of the street-car truck, a pinion engaging with the circular rack and a knuckle-coupling by means of which motion is transmitted from one of the axles of the friction-wheels to said pinion, substantially as and for the purposes specified. 95

2. The combination with the street-car, a trolley-pole having a swiveled connection of an inclined wire upon which the trolley-pole may run to assume a vertical position, a stationary circular rack, a rotatable plate mounted above said rack said plate having parallel 100

slots therein, friction-wheels the peripheries of which project through said slots in position to be engaged by the wheels of the car, a pinion engaging with said circular rack, and a coupling by means of which motion is transmitted from an axle of the friction-wheels to said pinion, substantially as and for the purposes specified.

In testimony that I claim the foregoing as my own I hereto affix my signature in presence of two witnesses.

OTTO G. RIESKE.
